UNITED STATES PATENT OFFICE.

WILLIAM H. RUMMEL, OF DUBOIS, IDAHO.

WRENCH.

1,245,035.

Specification of Letters Patent. Patented Oct. 30, 1917.

Application filed February 14, 1917. Serial No. 148,499.

To all whom it may concern:

Be it known that I, WILLIAM H. RUMMEL, a citizen of the United States, residing at Dubois, in the county of Fremont and State 5 of Idaho, have invented certain new and useful Improvements in Wrenches; and I do hereby declare the following to be a full, clear, and exact description of the invention, such as will enable others skilled in the art 10 to which it appertains to make and use the same.

This invention relates to a wrench of the type employing a shank having a stationary jaw and a movable jaw thereon and has for 15 one of its objects the provision of a means for locking the movable jaw at various adjusted positions upon the shank by operating the hand grip upon the shank.

Another object of this invention is to provide a plurality of rack teeth upon the shank 20 adapted to be engaged by a locking member carried by the movable jaw and which is forced into and out of engagement with the rack teeth by moving the hand grip toward 25 and from the movable jaw.

A further object of this invention is the provision of means secured to the hand grip and slidably connected with the locking member for forcing said locking member 30 into engagement with the rack teeth upon moving the hand grip away from the movable jaw which will lock the movable jaw upon the shank in various adjusted positions.

A still further object of this invention is the provision of a wrench of the above stated character, which shall be simple, durable and efficient and which may be manufactured and sold at a comparatively low 40 cost.

With these and other objects in view, as will become more apparent as the description proceeds, the invention consists of the novel features, combination and arrangement of parts, as will be hereinafter more fully described and claimed.

For a complete understanding of my invention, reference is to be had to the following description and accompanying drawing, in which:

Figure 1 is a bottom plan view of a wrench constructed in accordance with my invention.

Fig. 2 is a longitudinal sectional view of 55 the same,

Fig. 3 is a transverse sectional view taken on the line 3—3 of Fig. 2,

Fig. 4 is a detail perspective view of the locking member,

Fig. 5 is a perspective view of the means 60 for connecting the locking member to the hand grip,

Fig. 6 is a sectional view taken on the line 6—6 of Fig. 2.

Referring in detail to the drawing, the 65 numeral 1 indicates a shank having secured to one end the ordinary stationary jaw 2. A body 3 has formed on one end thereof, the ordinary movable jaw 4 and is slidably supported on the shank 1 by straps 5. The 70 body 3 is provided with a recess 6, in which is positioned a locking member 7. The locking member 7 has a straight inner face 8 on which a plurality of teeth 9 are formed and are adapted to intermesh with 75 teeth 10 formed upon the shank 1. The locking member 7 has an outwardly directed lug 11 formed upon its outer face and the outer face of the locking member 7 inclines in the direction of the lug 11 as shown at 12 80 and has formed thereon a tenon 13, thus it will be seen that the end remote from the end on which the lug 11 is formed, is of greater thickness.

A hand grip 14 is slidably mounted upon 85 the shank 1 and has oppositely disposed grooves 15 formed upon its inner face in which is adapted to travel a pin 16 carried by the shank.

Stops 17 are formed within the grooves 90 15 for engagement with the pin 16 to limit the movement of the hand grip 14 upon the shank. An arm 18 is secured to the hand grip by fasteners 19 and project forwardly 95 from the hand grip in the direction of the body 3. An extension 20 is formed upon the arm 18 and has oppositely disposed flanges 21 that are slidably received within grooves 22 of the body.

The extension 20 increases in thickness in 100 the direction of its free end to provide an inclined face 23 in which a dove-tail groove 24 is formed for slidably receiving the tenon 13 upon the locking member 7, thus it will be seen upon moving the hand grip 14 105 in the direction of the movable jaw 4 on the body 3, the extension 20 moves in engagement with the shoulder 11 upon the locking member 7, thus relieving the tension of the locking member against the shank or permit- 110

ting the teeth upon the locking member and shank to become disengaged, whereby the body 3 is free to slide upon the shank to adjust the jaws with relation to each other 5 to receive a nut or like device. After the jaws have been properly adjusted to fit the nut or the like, the hand grip 14 is slid upon the shank 1 away from the body 3, causing the extension 20 to slide upon the locking 10 member 7 and force the same in the direction of the shank, causing the teeth thereon to lock with the teeth upon the shank, thus locking the movable jaw and body against movement upon the shank. This 15 locking feature is accomplished owing to the inclined face 23 of the extension 20 and the locking face 12 of the locking member 7 being disposed in opposite directions so that when the enlarged portion of the locking 20 member and the enlarged portion of the extension are bearing against each other, the locking member is forced in the direction of the shank.

From the foregoing description taken in 25 connection with the accompanying drawings, it will be noted that a device has been provided whereby the movable jaw 4 may be readily adjusted with relation to the stationary jaw and after being adjusted can be 30 easily and quickly locked in said adjusted position by moving the hand grip 14 away from the body or the movable jaw upon the shank 1. When the hand grip 14 is in this 35 position, the locking action will be increased, owing to the fact that when the wrench is in use, there is always a tendency to pull upon the hand grip 14 and as the pull upon the hand grip 14 increases, the wedging action between the locking member 7 and the extension 20 increases, thus firmly locking the 40 movable jaw in any desired adjusted position.

While I have shown and described the preferred embodiment of my invention, it 45 will be understood that minor changes in construction, combination and arrangement of parts may be made without departing from the spirit and scope of the invention as claimed.

50 What is claimed is:

1. A wrench comprising a shank, a body 55 slideable upon the shank, a movable jaw formed upon the body, said body having a recess, a locking member located within said recess, teeth formed upon said locking mem-

ber, teeth formed upon the shank and adapted to engage the teeth of the locking member, a hand grip slideable upon the shank, an extension connected to the hand grip and slidably secured to the body and 60 engaging the locking member to cause said locking member to move toward and from the shank to disengage the teeth thereon with the teeth of the shank.

2. A wrench comprising a shank, a sta- 65 tionary jaw formed on said shank, a body slideable upon said shank, a movable jaw formed on said body, said body having a recess, the walls of said body having grooves, a locking member disposed within the re- 70 cess and having an inclined face, teeth formed on said locking member, teeth formed on the shank and engaging the teeth of the locking member, a hand grip slideable on the shank, an arm secured to said hand grip, an extension formed on said arm and having an inclined face for coöperation with the inclined face of the locking member, op- 75 positely disposed flanges formed upon the extension, and slideable in the grooves of the 80 walls of said body.

3. A wrench comprising a shank, a sta- 85 tionary jaw formed on said shank, a body slideable upon the shank, teeth formed upon the shank, a movable jaw formed on said body, said body having a recess, the walls of 90 said recess having grooves, a locking mem- 95 ber disposed within the recess and having an inclined face, a shoulder formed on said locking member, teeth formed on said lock- 100 ing member and adapted to intermesh with the teeth of the shank, a hand grip slideable upon the shank, an arm secured to the hand grip, an extension formed on said arm and having an inclined face for coöperation with the inclined face of the locking member, op- 105 positely disposed flanges formed on said ex- 110 tension and slideable in the grooves of the walls of the body, said extension having a dove-tail groove in its beveled face, and a tenon formed upon the beveled face of the locking member and slideable within the dove-tail groove of the inclined face of the extension.

In testimony whereof I affix my signature 105 in presence of two witnesses.

WILLIAM H. RUMMEL.
